CLAIM

The ornamental design for a top of wall vented finish bead, as shown and described.

DESCRIPTION

FIG. 1 is a top, front perspective view of a top of wall vented finish bead showing our new design;

FIG. 2 is a front view of the top of wall vented finish bead;

FIG. 3 is a back view of the top of wall vented finish bead;

FIG. 4 is a right side view of the top of wall vented finish bead;

FIG. 5 is a left side view of the top of wall vented finish bead;

FIG. 6 is a top side view of the top of wall vented finish bead; and,

FIG. 7 is a bottom side view of the top of wall vented finish bead.

The broken lines in the drawings illustrate portions of the top of wall vented finish bead that form no part of the claimed design.

1 Claim, 4 Drawing Sheets
